[57] CLAIM

The ornamental design for a table, as shown and described.

DESCRIPTION

FIG. 1 is a front elevational view of a table showing my design;

FIG. 2 is a left side elevational view thereof;

FIG. 3 is a top plan view thereof; and

FIG. 4 is a bottom plan view thereof.

The side not shown in FIG. 2 is a mirror image of the side shown.

FIG. 1

FIG. 4
